UNITED STATES PATENT OFFICE.

WALLER SCOTT, OF RICHMOND, VIRGINIA.

WASHBOARD.

No. 866,892.

Specification of Letters Patent.

Patented Sept. 24, 1907.

Application filed April 11, 1906, Serial No. 311,099.

To all whom it may concern:

Be it known that I, WALLER SCOTT, a citizen of the United States of America, and a resident of Richmond, county of Henrico, State of Virginia, have invented 5 certain new and useful Improvements in Washboards, of which the following is a full and clear specification, reference being had to the accompanying drawing, in which—

Figure 1 is a front view of the washboard partly 10 broken away; Fig. 2 a vertical sectional view thereof; and Fig. 3 a detail perspective of the double soap-receptacle.

This invention relates to that type of washboard in which the rub-board as well as the soap-box is double-faced for the purpose of making the board reversible, and the object of the present invention is to produce a board of that type which shall be strong and durable 15 and shall also be capable of being easily taken apart for cleaning and drying the parts, as more fully hereinafter 20 set forth.

To the accomplishment of this object and such others as may hereinafter appear, the invention consists of the parts and combination of parts hereinafter 25 fully described, and particularly pointed out in the appended claims, reference being had to the accompanying drawing forming a part of this specification, in which the same reference-characters designate like parts throughout the several views.

Referring to the drawing annexed by reference- 30 characters, *a* designates the wooden side braces each of which is grooved on its inner side from a point near its lower end continuously to its upper end. Clamped between these legs or side pieces is the corrugated rub-board *c* which is constructed of a single piece of galvanized steel transversely corrugated or otherwise roughened to provide duplicate rubbing surfaces upon opposite sides. The side edges of the rub-board are respectively fitted into the grooves in the side pieces, and the upper end of the rub-board as well as the lower end 35 thereof is curled to form a tube *d* through which is passed a rod *e* which passes through the side member and serves to connect the same and the interposed rub-board rigidly together. A conical head is formed on one end of each bolt or rod *e* and a conical nut is screwed 40 on the other end thereof, these conical parts being counter-sunk into the side members so as to be flush with their outer surfaces. As thus constructed the rub-board will not require any nails to fasten it in place and the rub-board and side members may be readily separated by simply removing the long bolts. This manner of constructing the body of the board not only enables it to be assembled with great despatch but also insures a very rigid construction when assembled.

A double-faced soap-holder is removably secured be-

tween the upper edges of the side members. This 5 soap-holder consists of a single sheet of metal folded about midway its length so as to entirely envelop a wooden cross-bar *b*, the two main parts *g'* of the plate being brought closely together to form the splash-plates of the two soap-receptacles, the side edges of 10 these two plates being passed down into the grooves in the inner sides of the side members. The part of the plate which envelops the cross-bar *b* is wider than the portions *g'*, so that the ends of the metal covered cross-bar project laterally a short distance from the side 15 edges of said plates *g'*, so that when the soap-holder is pushed down into place these projecting ends of the metal covered cross-bar will rest upon the upper ends of the side members. The lower end of each splash-plate *g'* is narrowed at *j* sufficiently to permit it to be 20 curled outwardly and upwardly to form a gutter *h* extending from side member to side member and being provided in its under side with a series of holes to permit the drainage from the soap to run down over the face of the rub-board. The plates *g', g'*, are separated 25 sufficiently to permit the upper end of the rub-board to pass up between them to a point beyond the perforations in the gutters.

It will be observed that the soap-holder is held in place by simply being slid down between the two side 30 members, the friction being sufficient to hold it in place in view of the fact that in use there is no tendency for the holder to be displaced. When in place the soap-holder tends to brace the upper end of the board, especially in view of the rigidity given to it by 35 enveloping the cross-bar in the sheet metal. By covering the cross-bar with sheet metal the detachable soap-holder is strongly braced and a very rigid body rest is provided for the washerwoman. It will be observed that this construction of soap-holder not only 40 avoids the use of nails or other fastening devices in securing it to the board, as stated, but also avoids entirely the use of nails in constructing it. In fact there is not a single nail used in the entire board, the two 45 long bolts or rods constituting the sole fastening devices.

It will be apparent to those skilled in the art that various mechanical embodiments of the invention are possible and I, therefore, do not wish to be limited to the exact arrangement and construction shown.

What I claim and desire to secure by Letters Patent is:

1. In combination, a pair of side members grooved each along its inner side, a double-faced rub-board whose edges lie in said grooves, and a double-faced soap-receptacle having its side edges slid down in said grooves from the top of the board, said soap-receptacle comprising a pair of splash-plates arranged back to back each of whose lower edges is curved outwardly and upwardly to form a gutter,

said soap-receptacle being formed of a single piece of sheet metal folded into a tube at its upper edge, and a cross-bar enveloped by said sheet metal tube, substantially as set forth.

2. In combination with side members and a rub-board therebetween, of a double-faced soap-receptacle adapted to slide down between the upper ends of the side members in grooves formed in the side members, said soap-receptacle being formed of sheet metal folded to form a tubular cross-bar at its upper end and a pair of gutters at its lower end,

the gutters extending over upon the faces of the rub-board and being perforated to discharge the drainage of the soap-receptacles onto the rubbing-board surfaces.

In testimony whereof I hereunto affix my signature, in the presence of two witnesses this 9th day of April 1906. 15

WALLER SCOTT
